UNITED STATES PATENT OFFICE.

ALBERT E. GOULD, OF GRAND RAPIDS, MICHIGAN.

WINDOW.

No. 926,735.

Specification of Letters Patent.

Patented July 6, 1909.

Application filed December 5, 1908. Serial No. 466,142.

To all whom it may concern:

Be it known that I, ALBERT E. GOULD, a citizen of the United States of America, residing at Grand Rapids, in the county of Kent and State of Michigan, have invented certain new and useful Improvements in Windows; and I do hereby declare the following to be a full, clear, and exact description of the invention, such as will enable others skilled in the art to which it appertains to make and use the same.

My invention relates to improvements in windows, and more particularly to the parting strip and weather strip features of the same, and its object is to provide a metallic strip that will serve both as a weather strip and parting strip; to provide a parting strip requiring no groove in the casing to receive the same, and to provide the device with various new and useful features, as hereinafter more fully described and particularly pointed out in the claims, reference being had to the accompanying drawings in which:

Figure 1 is a perspective detail of a portion of a window with my device applied thereto. Fig. 2 is a horizontal sectional detail of the same. Fig. 3 is an elevation of a portion of the casing showing the arrangement of my device thereon. Fig. 4 an enlarged detail in perspective of a portion of a strip made in accordance with my invention. Fig. 5 a horizontal sectional detail of a modification thereof applied to a window.

Like numbers refer to like parts in all of the figures.

My device consists essentially of a strip of sheet metal of suitable dimensions bent variously at right angles as shown in Fig. 4, in which 1 represents the middle portion of the strip bent twice at right angles and having parallel sides spaced apart whereby it is of the proper external dimensions to take the place of the projecting portion of the parting strips commonly used. Projecting oppositely in the same plane and from the base of this parting strip portion 1 are the base portions 2 and 2^a adapted to engage the inner surface of the casing and secured thereto by means of suitable fastenings or screws inserted in openings 4 therein. This base portion 2 is turned inward at right angles near its edge, and in the opposite direction to the strip portion 1, thus forming a narrow flange 5 adapted to be forced into the casing, which flange serves to stiffen the edge of the base 2

and at the same time forms an air-tight joint between the base and the casing. The other base portion is of suitable width to receive the fastenings and is thence turned outward 60 at right angles parallel with the strip portion 1 as at 3, and extends outward to about the same distance from the base portions. This portion 3 forms a weather strip adapted to enter a suitable groove or saw kerf in the 65 sash parallel with the edge of the sash and near the side adjacent to the parting strip. In the modification shown in Fig. 5 this flange 3 is prolonged and folded backward upon itself forming a flexible and yielding 70 extension 3^a which serves to more effectually close the groove and prevent the passage of air therethrough. However, the device operates quite satisfactory without this extension 3^a. This device when applied is divided 75 opposite the metal rails of the sash, and reversed to engage the groove in the respective upper and lower sashes 7 and 7^a. 6 represents the side of the casing which requires no groove to receive the parting strip and to 80 which is fastened the usual stops 8.

It will be noted that by means of this construction, I am able to altogether dispense with grooving the casing, and also that the parting strip and weather strip features are 85 combined in one strip and are easily applied, and that the groove in the sashes to receive the weather strip portion of the device is so close to one side of the sash as to in no wise interfere with the usual arrangement and location of the sash cord (not shown), or operation of the same, and also that this device is well adapted to be inserted in any window of ordinary construction by merely removing the parting strip therein, and grooving the 95 sashes with a saw to receive the portion 3 or 3^a.

What I claim is:—

1. A combined parting strip and weather strip, comprising a middle longitudinal portion adapted to form a parting strip, oppositely projecting base portions in the same plane and adapted to engage the surface of a window casing and to be secured thereto, and an outwardly projecting flange on the edge 100 of one of said base portions adapted to slide in a groove in a window sash, and spaced apart from the said middle portion.

2. A combined parting strip and weather strip for windows, comprising a strip of sheet 110 metal folded along the middle to form a parting strip and having oppositely extended

base portions to engage the surface of a window casing, the outer edges of said base portions being oppositely bent respectively to form flanges, one flange being narrow to be forced into a casing and the other being wider to slide in a groove in a sash of a window.

3. A combined parting strip and weather strip comprising a strip of sheet metal folded longitudinally at right angles and in parallel lines to form a middle portion to serve as a parting strip, oppositely projecting base portions to engage the surface of a window casing, an inwardly turned marginal portion on one base portion forming a narrow flange adapted to be forced into a window casing, and an outwardly turned portion on the outer edge of the other base portion forming a flange to slidably engage a groove in a window sash.
4. A combined parting strip and weather

strip, consisting of a strip of sheet metal folded longitudinally at intervals being folded on seven parallel lines to form a rectangular middle portion to serve as a parting strip, oppositely projecting base portions to engage the surface of a window casing and to be attached thereto, a narrow inwardly projecting flange at the outer edge of one base portion adapted to be forced into a casing, an outwardly projecting wider portion adapted to slidably engage a groove in a window sash, and a flexible margin folded upon the last named portion to yieldingly close the said groove.

In testimony whereof I affix my signature in presence of two witnesses.

ALBERT E. GOULD.
